UNITED STATES PATENT OFFICE.

GEORGE ENGER AND AUGUST KRESS, OF MILWAUKEE, WISCONSIN.

DESIGN FOR A PURSE-FRAME.

SPECIFICATION forming part of Design No. 20,995, dated August 18, 1891.

Application filed July 6, 1891. Serial No. 398,607. Term of patent 7 years.

To all whom it may concern:

Be it known that we, GEORGE ENGER and AUGUST KRESS, citizens of the United States, residing in Milwaukee, in the county of Milwaukee and State of Wisconsin, have invented and produced a new and original Design for the Top or Sides of Pocket-Books, Purses, or Analogous Articles; and we do hereby declare the following to be a full, clear, and exact description of the same, reference being had to the accompanying drawing, forming a part thereof.

Our design is intended to be materialized in or upon the top or side of a pocket-book, purse, or analogous article; and it comprises the representation of the fore part of an ancient Spanish ship or galleon of the fifteenth century, the representation of waves in the foreground and to the right of said ship and extending back to a mountainous coast in the background, having the representation of palm-trees on one of the hills of said coast. In the foreground, close to said ship, is the representation of an ancient row-boat with a group of people in it, some of whom are represented as rowing or steering said boat and some of whom are shown sitting, while others are standing, a figure standing in the prow of the boat holding aloft an unfurled banner with a cross delineated thereon, another of said figures standing and holding a cross, while still another figure is seated and carrying a battle-ax.

In the extreme lower front of the design there is represented a scroll for any suitable inscription, while in the upper background is represented a cloud extending from the right-hand limit of the rocky coast to the mast of the galleon, said cloud being intercepted about midway of its length by the representation of a compass.

Having thus described our design, what we claim therein is—

In a design for a purse-frame or analogous article, as herein shown and described, the top or side panel thereof comprising the representation of the fore part of an ancient Spanish galleon, the representation of waves extending to the right of the same and back to a mountainous coast, forming the background of the design, the representation of a boat adjacent to said galleon and having figures standing and seated therein, carrying emblems and weapons, the representation of a cloud in the upper background extending from one end of the design to the other, and the representation of a compass interposed about midway of the length of said cloud.

In testimony whereof we affix our signatures in presence of two witnesses

GEO. ENGER.
AUGUST KRESS.
